UNITED STATES PATENT OFFICE

FEEDING APPARATUS

James Carlyle Mobley and Bronson C. Skinner, Dunedin, Fla.; said Mobley assignor to said Skinner

Application September 22, 1944, Serial No. 555,252

10 Claims.

The present invention relates to feeding apparatus and, more particularly, to such apparatus adapted for feeding globular objects to suitable receiving means such as relatively moving receivers.

A general object of the present invention is the provision of simple and economically constructed and operated feeding apparatus adapted efficiently to feed substantially globular objects, such as citrus fruit or the like, from a common supply to and through a plurality of ways without undue tendency to jam, with each way delivering to separate receiving means, such as a succession of moving receiving recesses, in an accurate and secure manner.

A more specific object of the invention is the provision of such feeding apparatus characterized by means to provide or maintain a common haphazard supply of globular objects for a plurality of separate inclined ways into each of which is to be arranged a single file of the objects for successive delivery therefrom in an accurate and predetermined manner, the ways being so related to each other with respect to a successive foreshortening of the entrance ends thereof and upwardly moving means in the vicinity of the entrance ends being so adapted to engage the objects and agitate them as to assure in an efficient manner the arrangement of the objects in single file in the separate ways without any undue jamming.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had to the following detailed description taken in connection with the accompanying drawings, in which:

Fig. 1 is a side elevational view with parts in section and parts broken away of one embodiment of the present invention indicating one type of receiver with which the feeding apparatus may be advantageously associated;

Fig. 2 is a top plan view of the feeding apparatus shown in Fig. 1 with parts broken away;

Fig. 3 is a sectional elevation with parts broken away of another embodiment of the invention; and

(Cl. 198—30)

Fig. 4 is a view similar to Fig. 3 showing still another embodiment of the invention.

Some of the difficulties attendant upon placement of globular objects, such as oranges or the like, in moving receiving means such as receivers having cup-like recesses, especially those arising when citrus fruits are placed in such receivers to be carried to treating apparatus, have been pointed out in the Skinner et al. Patent 2,283,615 of May 19, 1942, and the Walker Patent 2,338,148 of January 4, 1944, such as a tendency of such objects to bounce out of the recesses of the moving receiver. Also when the feeding means comprises an inclined chute the objects, in addition to having a tendency to bounce, may become jammed in the chute or other fixed structure or between such feeding means and the receiving recesses of the moving receiver. Further, careful timing also may be required.

The present invention efficiently overcomes these and other problems and difficulties in a simple and efficient manner. It comprises a plurality of inclined ways down each of which globular objects are adapted to tumble in single file from a common supply thereof. These ways are successively foreshortened at their entrance ends a distance approximately equal to, or somewhat greater than, the average diameter of the objects, and movable means at the bottom of the ways at the vicinity of their entrance ends engage the objects and agitate them to prevent jamming at the entrances to the ways. These ways may then feed to rotated retard roller means which assure accurate placement of the objects in successions of recesses in a moving receiver.

In the drawings like numerals identify like parts throughout. As shown in Fig. 1 a receiver 10 may be a cylinder having in its surface 11 a succession of cups or recesses 12—12. Each cup 12 is preferably so shaped and of such size as to receive in a secure manner any one of a group of sized globular objects such as citrus fruits, or more particularly oranges such as those indicated at A. The receiver 10 may cooperate with suitable mechanism for halving the fruit and extracting the juice, or otherwise operating thereon, at succeeding stations.

The objects, e. g. oranges, may be supplied from any suitable source which may include a sizer belt over which the fruit is run to and under a sizer roll, as understood in the art. The sized objects may then be fed by any suitable means to the apparatus of the present invention such as a slat elevator 13 comprising a continuous belt 14 on which is transversely arranged a plurality

of slots 15—15. The elevator 13 carries the globular objects to the position indicated at 16 where they are permitted to roll from the elevator 13 into the entrance end 17 of the apparatus of the present invention. The endless belt 14 may be lapped around a roller 18 suitably supported by a shaft 19 to which may also be keyed a spur gear 20 adapted for use in the drive of mechanism of the present invention.

As shown in Figs. 1 and 2 the novel feeding apparatus may comprise a wide chute 21 adapted to receive at its entrance end 17 a haphazard supply of the globular objects or oranges. If this chute is to be employed in the separate feeding of a plurality of rows of receiving cups, such as three rows which may be staggered if desired as proposed in the above identified Walker patent, the objects must be taken from the common haphazard supply and arranged in three single files, or as many files as there are rows of receiving cups in the moving receiver, without undesired jamming. For this purpose the inclined chute 20 may be provided with a pair of dividing walls 22 and 23 which, together with side walls 24, 24 of the chute 21, provide three separate ways down each of which the objects are to tumble in single file.

Feeding into the three separate ways may be accomplished by foreshortening the entrance ends of the ways. Preferably such foreshortening is of a distance approximately equal to, or somewhat greater than, the average diameter of the objects so that feeding to all three ways in a uniform and efficient manner will be assured. This is indicated in both Figs. 1 and 2 wherein the dividing wall 23 is shown to be foreshortened about the diameter of one of the objects A with respect to the entrance end of the dividing wall 22.

In accordance with the development of the present invention it was unexpectedly found that jamming, or inefficient feeding or arrangement of the objects into the respective single files, could be effectively avoided at all times by the employment at the bottom of the ways in the vicinity of their entrance ends of object agitating means such as upwardly movable means to engage the objects and agitate them, thereby assuring that they will fill up the longer way, spill over and fill up the next longest way, and spill over again to fill up the successively shortened ways in an orderly fashion. In accordance with the preferred embodiment of the present invention this is preferably accomplished by a link belt structure 25, the upper stretch of which may extend substantially completely across the chute 21, a section of the bottom 26 thereof being preferably removed as is indicated in Figs. 1 and 2, and with the upper stretch of the link belt 25 serving as the bottom of the ways at least in the vicinity of their entrance ends.

The link belt structure may be rotatably supported on a pair of rolls 27 and 28 with the roll 27 fixed to a shaft 29 to which may be keyed a spur gear 30 meshed with the spur gear 20 to be driven from the latter. The roll 28 may also be fixed upon a rotatable shaft 31 to which may be keyed a pulley 32 about which a belt 33 may be lapped for the drive of other mechanism, as hereinafter indicated. Of course it will be understood that the belt structure 25 need not necessarily be a link belt structure, but the latter is preferred due to the uneven surfaces and projections provided thereby which assure a better

grip upon the surfaces of the globular objects to assure the effective agitation thereof.

The three ways, depicted by way of example, or resultant chutes provided by the side walls 24, 24 and dividing walls 22 and 23 may feed to any desired receiving means, but preferably are associated with the retard roller apparatus of the above identified Walker patent for the reasons therein indicated. Obviously the retard roller means may comprise three separate chutes each of which is aligned with one of the chutes provided by the above desirably subdivided chute 21. However, for the purpose of simplicity the three ways of the chute 21 may be continued to provide the three ways of the retard roller means as is proposed in Figs. 1 and 2.

In such case the two side walls 24, 24 may support in the vicinity of their lower ends a rotatable shaft 34 to which is keyed a pulley 35 to be driven by the belt 33. The lower end 36 of the chute 21 may thus constitute a delivering end terminating adjacent the cylindrical receiver 10 as shown. At this delivering end 36 a retard roller means 37 is preferably provided. This roller means may be a single roll structure suitably grooved in the vicinity of each of the three ways or it may comprise a plurality of hyperboloid elements 38—38, one for each of the ways as is indicated in Fig. 2. When the rollers 38—38 are so shaped they have the advantage of tending to center the objects regardless of the shape of the ways so that the objects fall into the middle of the cups 12—12 of the receiver 10, there to be properly located and securely seated. These retard rollers are preferably made of hard or unyielding material, but may be made of or surfaced with somewhat resilient material such as rubber or the like. These rollers are spaced from the bottoms of their respective chutes a distance sufficient to permit the fed objects to move by gravity past them to the receiver, and the distance between any portion of the surface of the cups 12—12 and an opposed portion of the surface of the rollers 38—38 is preferably slightly more than the distance between that portion of a cup surface and the opposed portion of the protruding surface of any object to be located therein so that the objects will pass freely beneath the rollers when the objects are properly seated in the receiving cups thereby permitting them to be carried away by movement of the receiver, all as is explained in more detail in the above identified Walker patent.

The chute 21 is inclined, as shown in Fig. 1, so that the globular objects will tumble down it and its respective ways due to the force of gravity. The inclination of the chute 21 may be at an angle of about fifteen to forty-five degrees, and the entrance portion thereof should be of sufficient length to obtain a free movement of the globular objects before they are diverted into the separate paths of the successive ways provided by the foreshortened dividing walls 22 and 23.

Although the structures shown in Figs. 1 and 2 are preferred, it is obvious that other agitating means may be provided, such as a pair of roughened rolls 39, 39, one of which has its periphery thereof rotated in a slot 40 in the bottom 26 of the chute somewhat medially of the way provided by the side wall 24 and dividing wall 22 in the vicinity of the entrance end thereof. The other roll 39 similarly has its periphery rotated in a slot in the bottom of the way provided by the dividing walls 22 and 23 also in the vicinity of the entrance end thereof. When the rolls 39, 39

are rotated in a suitable direction, such as indicated by the arrow in Fig. 3, it will be seen that each provides an upwardly movable means at the bottom of the ways in the vicinity of their entrance ends to engage the objects or fruit and agitate them so as to draw the fruit away from the entrance ends should there be any tendency for the same to jam at that location as they attempt to enter the different ways.

A similar end may be obtained by providing the upwardly moving means at the bottom of the ways in the vicinity of their entrance ends such as by the provision of an agitating plate 41 as proposed in Fig. 4. This plate 41 may be located in a slot 42 in the bottom of the chute structure 21 in the vicinity of the entrance ends of the successively foreshortened ways, and preferably extends substantially entirely across chute 21. In order to avoid any tendency for a downwardly moving surface to increase any jamming tendency, provision may be made for assuring that the plate 41 is held in the plane of the bottom 26 of the chute 21 only as it is slid upwardly from its lowermost position to its uppermost position. It may then be retracted out of the slot 42 so as to avoid engagement with the surfaces of the objects during return travel downwardly to its initial position. For this purpose the plate 41 may be suitably supported upon one or more arms 43 and one or more arms 44. The arm or arms 43 may carry a stud or shaft 45, and the arm or arms 44 may carry a similar stud or shaft 46. The studs or shafts 45 and 46 are slidably supported upon a surface 47 provided by an elongated slot 48 in an enlarged head 49 of a member 50 reciprocatively supported in any suitable manner such as by means 51. This reciprocating and plate control and guiding structure may be duplicated if desired.

The member 50 carries a pin 52 disposed in a slot 53 in the end of an arm 54 of a bellcrank lever 55, the other arm 56 of which is pivoted to a reciprocable control arm 57. A stop 58 may be provided for engagement by the arm 54 to determine the position of the head 49 for assuring that the plate 41 will be moved upwardly in the plane of the bottom 26 of the chute 21. Reciprocation of the plate 41 may be obtained in any suitable manner such as by an arm 59 having a slot 60 receiving the pin or shaft 46, and with the arm 59 pivoted to a reciprocable arm 61. The bellcrank lever 55 and the arm 59 may be pivotally mounted in any suitable manner such as upon a common shaft 62.

In operation of the embodiment shown by way of example in Figs. 1 and 2 the elevator or slat conveyor 13 carries oranges up to the position 16 and dumps them into the entrance end 17 of the chute 21. This is done in a haphazard manner without any attempt to segregate, align, or pre-arrange the oranges. The latter then start rolling down the inclined chute 21 over the bottom surface provided by the upwardly moving top stretch of link belt 25. They then continue to tumble down the surface of the moving link belt a sufficient distance to obtain a free movement, after which they approach the entrance ends of the three ways provided by the side flanges 24, 24 and the foreshortened dividing walls 22 and 23. If there is any tendency to jam at the entrance ends to these separate ways, movement of the link belt upwardly agitates the oranges and tends to draw them away so that they will properly tumble into the separate ways in single file. The foreshortening of the dividing walls 22 and

23 by a distance approximately equal to, or somewhat greater than, the average diameter of the oranges assures that all three ways will be effectively fed or supplied. As a result three separate single files of oranges are developed and these roll down the separate ways to the delivering end 36 of the chute 21 there to be properly guided and controlled in their movements by the retard roller structure 37 so that they will be quietly fed into the receiving cups 12-12 of the receiver 10 as these cups are carried successively past the delivering end 36 of the chute.

In a practice of the invention an embodiment of the modification proposed in Figs. 1 and 2 includes a link belt structure the upper stretch of which is about three and one-half feet long, and the ways from the lower end of the link belt structure to the delivering end at the retard roller means 37 are about eight to ten inches long.

10 This apparatus is being effectively used in efficient attainment of the desired operations outlined above.

15 It will thus be seen that the objects set forth are efficiently attained by the apparatus of the present invention, and the invention accordingly comprises the features of construction, combination of elements and arrangement of parts, which will be exemplified in the construction herein-after set forth and the scope of the invention will 20 be indicated in the claims.

25 It is also to be understood that the following claims are intended to cover all of the generic and specific features of the invention herein described, and all statements of the scope of the 30 invention which, as a matter of language, might be said to fall therebetween.

Having described our invention, what we claim as new and desire to secure by Letters Patent is:

1. A feeding device comprising, in combination, 40 a plurality of inclined ways down each of which globular objects are adapted to tumble in single file, said ways being successively foreshortened at their entrance ends a distance at least as great as the approximate average diameter of the objects, means to provide a common supply of objects for said ways, and means in the vicinity of the entrance ends of the ways to engage the objects and tend to move the engaged portions thereof in a direction generally opposite that 45 which the objects move down the inclined ways under the force of gravity to agitate the objects and thereby avoid jamming at the entrance ends.

2. A feeding device comprising, in combination, 50 a plurality of inclined ways down each of which globular objects are adapted to tumble in single file, said ways being successively foreshortened at their entrance ends a distance at least as great as the approximate average diameter of the objects, means to provide a common supply of 55 objects for said ways, and upwardly movable means at the bottom of the ways in the vicinity of their entrance ends to engage the objects and agitate them.

3. A feeding device comprising, in combination, 60 a plurality of inclined ways down each of which globular objects are adapted to tumble in single file, said ways being successively foreshortened at their entrance ends a distance at least as great as the approximate average diameter of the objects, means to provide a common supply of 65 objects for said ways, and means providing upwardly movable surfaces constituting the bottoms of said ways at their entrance ends.

4. A feeding device comprising, in combination, 70 a plurality of inclined ways down each of which

globular objects are adapted to tumble in single file, said ways being successively foreshortened at their entrance ends a distance at least as great as the approximate average diameter of the objects, means to provide a common supply of objects for said ways, endless belt means constituting the bottoms of said ways at their entrance ends, and means to drive said belt means in a direction whereby upper surfaces thereof will travel upwardly along said ways.

5 5. A feeding device comprising, in combination, a plurality of inclined ways down which globular objects are adapted to tumble in single file, a plurality of dividing walls separating said ways from each other successively foreshortened a distance at least as great as the approximate average diameter of the objects, means to provide a common supply of objects for said ways, and upwardly movable surfaces constituting the bottoms of said ways at their entrance ends.

10 6. A feeding device comprising, in combination, a plurality of inclined ways down which globular objects are adapted to tumble in single file, a plurality of dividing walls separating said ways from each other successively foreshortened a distance at least as great as the approximate average diameter of the objects, means to provide a common supply of objects for said ways, an endless belt having an upper stretch constituting the bottoms of said ways at their entrance ends, and means to drive said belt in a direction whereby the upper stretch travels upwardly along said ways.

15 7. A feeding device comprising, in combination, a plurality of inclined ways down each of which globular objects are adapted to tumble in single file, said ways being successively foreshortened at their entrance ends a distance at least as great as the approximate average diameter of the objects, means to provide a common supply of objects for said ways, endless link belt means constituting the bottoms of said ways at their entrance ends, and means to drive said belt means in a direction whereby upper surfaces thereof will travel upwardly along said ways.

20 8. A feeding device comprising, in combination, a plurality of inclined ways down which globular objects are adapted to tumble in single file, a plurality of dividing walls separating said ways from each other successively foreshortened a distance at least as great as the approximate average diameter of the objects, means to provide a common supply of objects for said ways, an endless link belt having an upper stretch constituting the bottoms of said ways at their entrance ends, and means to drive said belt in a direction whereby the upper stretch travels upwardly along said ways.

25 9. A feeding device comprising, in combination, an inclined chute, means to supply globular objects to the upper end of said chute, a plurality of dividing walls extending longitudinally of said chute and dividing it into a plurality of separate ways, said dividing walls terminating at their upper ends short of the entrance end of said chute and being successively foreshortened at their upper ends a distance at least as great as the approximate average diameter of the objects, an endless belt having an upper stretch constituting the bottom of said chute at the upper ends of said dividing walls, and means to drive said belt in a direction whereby the upper stretch travels upwardly.

30 10. A feeding device comprising, in combination, an inclined chute, means to supply globular objects to the upper end of said chute, a plurality of dividing walls extending longitudinally of said chute and dividing it into a plurality of separate ways, said dividing walls terminating at their upper ends short of the entrance end of said chute and being successively foreshortened at their upper ends a distance at least as great as the approximate average diameter of the objects, an endless link belt having an upper stretch constituting the bottom of said chute at the upper ends of said dividing walls, and means to drive said belt in a direction whereby the upper stretch travels upwardly.

JAMES CARLYLE MOBLEY.
BRONSON C. SKINNER.
